RECORD CONTROLLED PRINTING MACHINE

Samuel M. Taylor, Bluefield, W. Va.

Application June 27, 1947, Serial No. 757,605

10 Claims. (Cl. 101—93)

1

This invention relates generally to the class of typing machines adapted to make a typewritten record from a punched or perforated tape. More specifically the present invention is directed to a new and improved typing machine of this character having means for setting up, selectively at will, any one of a plurality of signal or search circuits responsive to predetermined tape punchings individual thereto whereby the locations on the tape of the punchings corresponding to a selected circuit may be indicated by a visual signal upon closing of the circuit as the tape is moved through the machine and, as such signal is received, a typewritten record of the information corresponding to the located punchings being taken as a basis of selection and tabulation.

This typing machine is particularly well suited, although not necessarily so limited, for use with a continuous property record system for electric power utilities; such a record system is used to meet the accounting requirements of the Federal Power Commission's Uniform system of accounts.

Under the Federal Power Act of 1937, the cost of an electric plant is based on its original cost at the time of installation, and records must be set up so that the cost may be determined on a monthly basis. Likewise, property which is retired from service must be retired at its original cost. The electric plant account, as set up in the Uniform system of accounts, is divided into several accounts under the general headings of Generating plants, Transmission and Distribution systems, Substations, and General. Each of these accounts is numbered.

Under the Uniform system of accounts all property is regarded as made up of units. A unit of property may be regarded as an assembly of a major item and the smaller items required for its installation. This assembly is assigned a number according to a material catalogue of units.

An electric plant is subject to depreciation and various changes have to be made to meet load conditions and demands for service. These changes must be made under a work order system, and the material and labor involved must be set up so that the units of property can be established and the cost determined. A number is assigned to each work order.

Records must be kept as to the various locations of the property of an electric plant which may cover vast areas extending into several States. Records must be kept for each taxing district such as State, county, municipality, and school districts. A number is assigned to each

of these taxing districts and also to each generating plant, substation, pole and tower.

A continuous property record system consists of an installation phase which involves setting up a history record for each property location and a set of total quantities or summary records for each unit of property in each taxing district.

A history record provides a permanent record for each location and carries information in regard to the taxing district, property location number, units of property, quantities, and installation dates with space provided for the addition of retirement dates. Space is also provided for future additions and changes and for the work order under which it is done. The information carried in the history records is obtained from field inventory sheets prepared by field engineers, and the material listed is coded by reference to the unit catalogue.

The total quantities or summary records are made up from the history records by a process of segregating and tabulating the like units of property listed thereon.

The history records serve as intermediate records between the operating and accounting departments. After the history records are installed, they are maintained by the operating department, and the unit costs are determined through the work order system. The accounting department is interested only in the total quantities of each unit for each taxing district.

The maintenance phase of a continuous property record system involves the reporting of additions and retirements for each accounting period. The date of installation for each unit of property is also of concern when the retirement of the unit is reported.

According to the continuous property record system disclosed herein in connection with the typing machine of the present invention, a six digit numbering system is employed to designate units of property, and the six digit numbers preferably are applied directly to the inventory sheets at the time the inventory is made in the field. The several digits of each unit number has a particular significance, the first digit indicating the account number, the second and third digits the class of property, and the fourth, fifth, and sixth digits the descriptive material.

Thus, the number 101645 in a Transmission and distribution system account indicates a creosoted pine pole, class 6, height 45 feet.

The coded information on the inventory sheets is transferred to a seven column tape providing a digit per line and two punches per digit. Fif-

teen lines on the tape, which involves 15 digits, produces one line of typing on the typing machine. This line of typing appears in five columns of numbers under the following headings:

Multi-plier	Quan-tity	Unit of property	Installa-tion date	Retire-ment date
1 digit	4 digits	6 digits	2 digits	2 digits

The multiplier is used for conductors. The span length or distance between poles times the number of conductors gives the quantity in feet. This column is used only in a few cases. All four digits under Quantity are not required in each case. In a great many cases the Quantity will involve but one digit. The number for the Unit of property will always be six digits, and the installation and retirement dates will always be two digits.

In setting up the record on the tape, the location number is recorded first as a unit of property as no quantity or dates are involved. This is followed by a recording of the number corresponding to each unit of property at that location together with the multiplier, quantity and installation date numbers associated therewith. The retirement date is not recorded at this time. The recording of each unit of property, as indicated heretofore, requires fifteen lines on the tape. When the last of the units at each location is recorded, a signal is recorded on the tape as a retirement date. A combination of punchings is used for this purpose which does not cause a number to be printed under the retirement date column when the typing machine is operated, but merely closes a circuit to a signal lamp for informing the operator that all of the units for a given location have been recorded. This leaves the necessary combination of punchings which can be made on the tape to record the retirement date of the last unit of property upon retirement thereof.

A separate tape is used for each taxing district and, when necessary, a separate tape can be set up for each substation and generating plant. The tapes are wound on reels and are of varying lengths according to the amount of property recorded thereon, the maximum being in the order of 3000 feet. Each tape is labeled as to the kind of property and the taxing district.

In preparing a history record from a particular tape, the tape is placed in the typing machine and the machine is operated to print a line at a time, the first line giving the location number and the subsequent lines giving the units of property and associated quantities and installation dates. When the last unit for a given location number is typed, the signal light appears and the paper is then advanced one full sheet length and torn off. When all such sheets have been obtained from a single tape, they are bound together into a history volume and stamped as to taxing district and kind of property.

The typing machine comprises a selector switch mechanism through which the tape is passed in contact with a plurality of switch elements of which there is one for each possible punching in the tape for each fifteen line section thereof. Each switch element is adapted to move through the tape to contact a companion switch element when the punching in the tape which corresponds thereto is moved into alignment therewith. The

typing machine also comprises fifteen typing bars, one each for the fifteen digits adapted to be typed by the machine in each line of typing thereof, and each typing bar is provided with ten imprint characters numbering 0 to 9. Electrical means under control of circuits established by the aforesaid selector switch mechanism for each unit setting of the tape are employed to cause the typing bars to be moved during the forward manipulation of the manual operating lever of the machine into the proper positions to type the numbers corresponding to the punchings in the tape for each particular setting thereof. At the end of the forward movement of the manual lever, the imprint mechanism is operated to move the paper into contact with the preselected imprint characters on the several typing bars. During the return movement of the manual lever, the typing paper is advanced one line and the tape is advanced fifteen lines to a new unit setting.

The typing machine further comprises a jack panel having a plurality of jacks and plug ended cords for use therewith and a key panel having a plurality of normally closed keys of the push button type used in telephone switchboards. The jacks and keys are connected in the aforesaid control circuits of the selector switch mechanism, there being a key on each side of each pair of companion switch elements of the mechanism and a jack interposed between each key and the switch element connected thereto. By reason of this arrangement, each pair of companion switch elements may be cut out of the typing bar control circuit therefor and cut into a search circuit by manipulation of the necessary cords and the jacks, individual thereto. A single pair of companion switch elements may be employed separately in the search circuit, as when the account number is made the basis of selection, or several pairs of elements may be connected in series in the search circuit, as when a unit of property is made the basis of selection.

Thus, in preparing the total quantities of units or summary records from the tape, a search circuit, which includes a lamp, is set up for a particular unit of property, and the tape is moved manually through the selector switch mechanism. When a section of the tape having punchings thereon corresponding to the particular unit number moves into the selector mechanism, the search circuit is closed and the lamp is lighted. The typing machine is then operated, as before, to type the quantity and installation and retirement dates. The entire tape is scanned in this manner to provide a typewritten summary sheet which gives the quantities, which may be totalled by means of an adding machine or comptroller, and the installation and retirement dates of all the like units of property in a given tax district.

The history volume is delivered to the operating department, and the summary sheets are delivered to the accounting department for use in determining plant cost, taxes, etc. The history volume contains all information essential from an operating standpoint. All changes which have been made are recorded in this volume and at the end of each accounting period, the volume is delivered to the records department. The changes which have been recorded in pencil in the history volume are recorded on the tape, and if the changes have been extensive, a new history volume is prepared, retired property being omitted by setting the typing machine so as not to type the retired units. A

new summary sheet is required if any changes have been made. This summary sheet includes only the additions and retirements. The retirements have to be shown according to the date of installation in order that the book cost may be applied as of the installation date. In this case, the retirement date is the basis of selection, whereby the typewritten record obtained from the typing machine includes a unit of property and an installation date.

An object of the present invention is to provide a new and improved typing machine of the type adapted to be operated from a punched tape.

Another object is to provide a typing machine adapted to type a large number of digits in a single line for each operation of the machine and in which each digit may vary from 0 to 9 in accordance with the punchings on the tape.

Another object is to provide a typing machine of this character in which the imprint character selection, imprint operation, and paper and tape advancements are all accomplished by the manipulation of a single operating lever of the machine.

A further object is to provide a new and improved selector switch mechanism and digit code therefor adapted to set up control circuits to effect a digit variation and imprint character selection from 0 to 9.

A still further object is to provide a typing machine having control circuits which facilitate the setting up of scanning or search circuits in selecting and locating predetermined punchings on the tape which correspond to information forming a basis of selective typing to be performed on the machine.

Still other objects, features and advantages of the present invention will become more clearly apparent from the following specification taken in connection with the accompanying drawings wherein:

Figure 1 is a view in elevation of the front of the typing machine of the present invention;

Figure 2 is a side elevation of the machine as viewed from the left in Figure 1;

Figure 3 is a side elevation of the machine as viewed from the right in Figure 1;

Figure 4 is a somewhat enlarged sectional view of the machine as seen along the line 4-4 of Figure 1;

Figure 5 is a view similar to Figure 4 but showing the position of the moving parts when the operating lever has been moved into the forward position thereof;

Figure 6 is a sectional view taken along the line 6-6 of Figure 4;

Figure 7 is a sectional view taken along the line 7-7 of Figure 6;

Figure 8 is a sectional view taken along the line 8-8 of Figure 6;

Figure 9 is a sectional view taken along the line 9-9 of Figure 4;

Figure 10 is a view in perspective of fragmentary portions of the rocker arm and sliding contact panel;

Figure 11 is a sectional view taken along the line 11-11 of Figure 8;

Figure 12 is a perspective view of a typing bar;

Figures 13a and 13b are diagrammatic views of fractional portions of a complete electrical system for the typing machine of the present invention; and

Figure 14 is a plan view of the jack and key panels for the machine.

Referring now to the drawings for a more complete understanding of the invention, and more particularly to Figures 1 to 3, it will be seen that the typing machine is supported on a framework comprising four uprights 10, and horizontal frame members 11 through 15. The framework is additionally strengthened at the front by a jack panel 16 and a key panel 17.

The roll of tape 18 is supported on a rod 19, 10 in turn, supported on frame members 13 and 15. The tape is passed upward through an opening 21, Figure 8, in the bottom of a casing 22 which is supported on the framework and houses the selector switch mechanism generally designated 23. This mechanism comprises a pair of insulation blocks 24 and 25 which are maintained in spaced relation by spacer members 26, Figure 11, to provide a channel therebetween through which the tape is drawn. This block assembly is secured in position in casing 22 by suitable brackets 27, Figure 6. Block 24 is provided with a plurality of transverse holes 28 for slidably receiving a plurality of bar-shaped contact or switch elements designated 29. It will be understood that there is one such switch element for each possible punching in the tape for each unit setting or 15 line sections thereof within selector mechanism 23. A cup-shaped housing 31 of suitable insulation material is secured to block 24 and is provided with a plurality of holes 32 in the top thereof through which the upper portions of switch elements 29 pass whereby the housing 31 serves to maintain the switch elements in position for free slidable movement under the force of gravity. Switch elements 29 thus bear against the tape 18 between blocks 24 and 25, and when a hole or punching 33 appears under a switch element, the switch element falls through the tape to contact a companion switch or contact element 34. Switch elements 29 are suitably formed at the top, preferably as shown, so as to serve as terminals for the connection of conductors or wires thereto, and are preferably rounded at the bottom to facilitate sliding movement of the tape and sliding movement of the switch elements through the punchings therein. Switch elements 34 may be round headed brass screws with the heads mounted flush with the top surface of block 25 and secured to the block by nuts 35 which also may serve as terminal nuts for securing wires or conductors to switch elements 34, preferably as shown.

Tape 18, upon entering housing 22, first passes over a suitable idler roller 36, thence through blocks 24 and 25, thence over a drive roller 37 having sprocket teeth 38 for engaging perforations 33 on the sides of the tape whereby the tape is drawn through the blocks upon rotation of drive roller 37 in the direction of the arrow, Figure 8, and thence outwardly of the casing through opening 41 therein. Roller 37 is secured to a shaft 42 which is suitably journaled in casing 22, and the shaft on one side of the casing has a crank 43 secured thereto and on the other side of the casing carries a ratchet wheel 44 for rotation therewith. Casing 22 preferably is provided with a top 45 which is hinged thereto as at 46 and has a snap type locking arrangement at 47 whereby the casing may be opened to render the selector switch mechanism 23 readily accessible for repair.

Shaft 42 extends through a casing generally designated 48 which houses the typing machine proper and is further journaled in the end walls 75 49 and 51 of this casing. Casing 48 further com-

prises a back wall 52 having a suitable opening 53 therein for access to the typing machine enclosed within the casing. Opening 53 preferably is closed by a door 54 which is hinged to back wall 52 as at 55 and has a convenient knob 56 for facilitating opening of the door.

Back wall 52 merges into top wall 57 which extends diagonally upwardly to merge with an arcuate wall portion 58 which is formed concentrically with respect to shaft 42. The arcuate wall merges as at 59 with a front wall portion 61, and the casing is enclosed at the bottom thereof by bottom wall portion 62 which is supported on, and suitably secured to, the upper longitudinal framework members.

Fifteen identical typing bars, each having a central opening 60 and generally designated by the numeral 63, are loosely pivoted on shaft 42 and maintained in the spaced axial relation thereon best indicated in Figure 6 by any suitable spacing means such, for example, as by washers and collars, not shown. Each typing bar comprises a pair of diametrically opposed circular segments 64 and 65, Figure 12. Segment 64 is the heavier of the two segments whereby this section is normally urged downwardly under the influence of gravity against a suitable stop 66. The arcuate face of segment 64 is provided with a set of imprint characters 67 numbering 0 to 9. These may be secured to the typing bar in any convenient manner, or may be formed integrally therewith if desired. The arcuate face of segment 65 is formed with a series of ten ratchet teeth 68 by means of which the typing bar may be moved pivotally on bar 42 to bring a desired imprint character thereon into the proper position with respect to the imprint mechanism, as will appear more fully hereinafter.

Also pivotally mounted on shaft 42 is a rocker arm assembly generally designated 69 which comprises an arcuate panel 70, concentrically arranged with respect to arcuate wall 58 of casing 48, and a pair of arms 71 and 72 formed preferably integrally with panel 70 and having suitable openings for loosely receiving shaft 42.

Panel 70 has secured thereto a pair of brackets 73 and 74 which, in turn, have a plurality of operating magnets 75 carried thereby. There is an operating magnet for each of the fifteen typing bars, seven of the operating magnets being carried by bracket 74 and the other eight by bracket 73. The magnets are staggered in brackets 73 and 74 so that the armatures 76 of the magnets are positioned directly above the typing bars 63 respectively, as best appears in Figures 1, 4 and 5. The armatures for the operating magnets carried by brackets 73 are pivotally mounted and maintained in spaced relation in any suitable manner on a shaft 77 which is supported in brackets 78 and 79. Similarly, the armatures of the operating magnets carried by bracket 74 are pivotally carried on a shaft 81 supported in brackets 82 and 83.

The rocker arm 69 carries a manual operating bar or lever 84 which is supported on panel 70 in spaced relation therewith by suitable posts 85 and 86. Arm 71 of rocker arm assembly 69 carries a pawl 87 for engagement with ratchet wheel 44 on the return or upward movement of the rocker arm assembly, thereby to rotate shaft 42 and advance the tape, as will appear more fully hereinafter. Each of armatures 76 is shaped as a pawl as at 88 and extends through openings 80 and 100 in panel 70 and arcuate wall 58 respectively into engagement with the ratchet teeth 68

on the typing bar individual thereto when the operating magnet for the armature is excited as the rocker arm assembly is moved downwardly.

This is accomplished by means of the arcuate 5 sliding contact panel 89 which is formed concentrically with respect to arcuate wall 58 and arranged adjacent thereto on the inner side thereof, as by being secured to end wall portions 49 and 51. Contact panel 89 preferably is formed of electrical insulation material whereby the pairs of sliding contacts 90 and 91 are carried thereby insulated from each other. There is a row of ten pairs of these contacts for each operating magnet, the ten pairs of contacts corresponding 15 respectively to the ten ratchet teeth on the typing bar associated with the operating magnet. For each row of these contacts there is a pair of cooperating contact pins 92 and 93 carried by moving panel 70 and adapted to slidably engage 20 successive pairs of contacts 90 and 91 as the rocker arm assembly 69 is moved downwardly. Panel 70, for this purpose, preferably is formed of suitable electrical insulation material whereby the pairs of contacts 92 and 93 may be insulated 25 from each other. These contacts are connected to the ends of the winding of the operating magnet individual thereto, as may best be seen in Figure 9.

Sliding contacts 90 and 91 are secured to panel 30 89 as by screws 94 which may also serve as binding posts for conductors or wires secured thereto.

A roll of paper 95 is carried on a rod 96 which is, in turn, supported in brackets 97 and 98 secured to bottom plate 62 of casing 48. The paper 35 from the roll is drawn over a roller 99, thence between this roller and an idler roller 101 in rolling contact therewith, and thence under a second idler roller 102 and outwardly of casing 48 through an opening 103 in front wall 61.

Rollers 99 and 101 are pivotally supported in a pair of L-shaped brackets or levers 104 and 105 which, in turn, are pivotally supported as at 106 in brackets 107 secured to bottom plate 62 of casing 48. Bracket levers 104 and 105 are slotted 45 as at 108 whereby the levers may be adjusted along pivotal point 106 so that the portion of paper 95 in contact with the imprint characters 67 on the typing bars 63 moves with the characters during the final downward movement of 50 the rocker arm assembly, the lower edge of panel 70 thereof engages the upturned end portion 109 of levers 104 and 105 causing them to rock about pivots 106, thereby to move the paper on roll 99 into contact with the imprint characters through 55 inking ribbon 110.

The ribbon 110 is carried in the usual spools 111 which in this case are driven through bevel gears 112 from a ratchet wheel 113. The ratchet wheel, in turn, is driven by a pawl 114 which is 60 pivotally secured as at 115 to a lever 116 in turn, pivotally supported on end wall 49 as at 117. The other end of lever 116 extends through an opening 118 in top wall 27 and terminates in a horizontal end portion 119 adapted to be yieldably urged against the upper edge of panel 70 by a spring 121 acting on the lever, whereby end portion 119 follows the panel upon downward movement of rocker arm assembly 69 to cause pawl 114 to slip over ratchet wheel 113 and engage another tooth thereon, movement of lever 65 116 in this direction being limited by stop 122. When panel 70 is restored to its initial position during the return movement of rocker arm assembly 69, the edge of the panel engages and 70 drives end portion 114, thereby to forcibly return 75

lever 116 to its position in Figure 7 whereby the ratchet wheel 113 is advanced one tooth and ribbon 110 is advanced to a new setting.

Paper 95 is advanced one line on the machine in a similar manner. For this purpose, roller 59 carries a ratchet wheel 123 which is engaged by a pawl 124 pivotally secured as at 125 to a lever 126 which is pivotally secured to end wall 51 of casing 48 at 127. The other end of lever 126 extends through an opening 128 in top plate 51 of casing 48 and terminates in a horizontal end portion 129 for engagement with the edge of panel 70 under power of spring 131. Forward movement of end portion 129 under power of spring 131 is limited by stop 132. Operation of lever 126 to advance ratchet wheel 123 forward one tooth is the same as operation of lever 116 in advancing ratchet wheel 113 forward one tooth and the previous description of the operation of the latter ratchet wheel, therefore, will suffice for both.

Imprint levers 104 and 105 extend through suitable openings 133 therefor in front wall portion 61.

The jack panel 16 comprises a plurality of jacks 134 for receiving plug ended cords as in conventional switchboard practice. There are two jacks for each pair of selector switch elements 29 and 34 these being electrically connected on either side of the switch comprising a pair of elements. An additional pair of jacks 135 and 136 connected to the incoming power line, which may be a conventional 110 volt source, are also provided. The jack panel further carries a search lamp 137, a location lamp 138, and an off-on power switch 139.

The key panel 17 comprises a plurality of keys 141 of the normally closed push button type which open the circuits therethrough when the keys are pushed. There is a pair of keys for each pair of selector switch elements 29 and 34, the keys being connected to the jacks individual thereto.

A selector switch code is employed for electrically connecting the sliding contacts of each row of contacts on panel 89 to the proper switch elements 29 in the selector switch mechanism 23. This code and lead connection designation is as follows:

B1-G1=0
B1-G2=1
B1-G3=2
B1-G4=3
B2-G1=4
B2-G2=5
B2-G3=6
B2-G4=7
B3-G1=8
B3-G2=9
B3-G3= }
special operating signals
B3-G4= }

By reason of this arrangement each sliding contact 90 in each row is connected to B lead 1, 2 or 3 and each contact 91 of each row is connected to G lead 1, 2, 3 or 4. This means that the winding of each operate magnet 15, when energized, is connected on one side to a B lead and on the other side to a G lead. All of the B leads 1, 2 and 3 are connected together and to the live side of the power source supplying the typing machine, and all of the G leads 1, 2, 3 and 4 are connected together and to the grounded side of the power source.

In the operation of the typing machine to

produce a history sheet, tape 18 is fed through selector switch 23 by means of crank 43 until the first group of punchings on the tape is reached. These will be the punchings for the location number. Lever 84 is then moved down. During the downward movement of panel 70, various pairs of contacts 92 and 93 in the digit rows under Unit of property (Figures 13a and 13b) will be momentarily energized by certain pairs of contacts 90 and 91 for the reason that certain pairs of selector switch elements 29 and 34 corresponding thereto in the Unit of property digit columns will be closed in accordance with the punchings in the tape corresponding to the location number. This will cause momentary energization of certain operate magnets 15, and as the magnets are energized their armatures will move into engagement with the ratchet teeth on the typing bars individual thereto whereupon the typing bars will be moved with the rocker arm assembly 69 to move the imprint characters 67 on the typing bars into a position to be engaged by the paper as the imprint mechanism operates during the final movement of the rocker arm assembly. This action is illustrated in Figures 4 and 5 wherein sliding contacts 90 and 91 corresponding to imprint character 6 have been energized, thereby to cause the operate magnet to pick up the foremost typing bar 63 in Figures 4 and 5 as pawl 76 moves to engage the fourth ratchet tooth down, which ratchet tooth corresponds to imprint character number 6 on the bar. As the energizing circuit to the operate magnet is broken, as contacts 92 and 93 move on to the successive pairs of sliding contacts 90 and 91, operation of the magnet is continued for a sufficient length of time by the use of shading coils or rings on the magnet, these being conventional and therefore not shown.

Assume that the foremost typing bar of Figures 4 and 5 corresponds to the operate magnet 15 of the thousands digit under the Unit of property column of Figures 13a and 13b. The circuit to operate this magnet and cause its armature to engage the fourth ratchet tooth down, as in Figure 5, is traced as follows: from the live side of the power source through power off-on switch 139, conductor 142 and the common B lead to the lower B2 lead which is herein also designated as conductor 143 for purposes of illustration, lower B2 key 141, lower B2 jack 134, B2 switch elements 34 and 29, upper B2 jack 134, upper B2 key 141, upper B2 lead herein also designated as conductor 144 to facilitate tracing of the circuit, sliding contact 90 corresponding to imprint character number 6, pin contact 92, winding of magnet 15, pin contact 93, sliding contact 91 corresponding to imprint character 6, upper G3 lead which is also designated as conductor 145, upper G3 key 141, upper G3 jack 134, G3 switch elements 29 and 34, lower G3 jack 134, lower G3 key 141, lower G3 lead also designated as conductor 146, and thence through the common G lead to ground potential at the other side of the power source.

On the return movement of the rocker arm assembly 69, the typing bars are released and fall under influence of gravity to the position of Figure 4, the ribbon 110 is moved to a new setting, paper 95 is advanced a length corresponding to the spacing between adjacent lines of typing thereon, and the tape is advanced 15 lines through the selector mechanism 23 by action of pawl 87 which engages ratchet wheel 44 during

the return motion. A new set of circuits is now established by the selector mechanism whereby multiplier, quantity, unit of property and installation date numbers are printed on the paper when lever 84 is moved downwardly. After a series of such operations have been performed, lamp 138 on jack panel 16 will light, thus indicating that all units of property have been recorded for the particular location number recorded. The paper is then withdrawn a full sheet length and torn off.

In preparing a summary sheet, a search circuit is built up on the jack panel according to the number of the unit of property to be tabulated. Assume, by way of example, that the number is 753024. This number corresponds to the following combination of B and G leads:

Number	Digit	B lead	G lead
7	Hdn. Thous.	B2	G4
5	Ten Thous.	B2	G2
3	Thous.	B1	G4
0	Hdrs.	B1	G1
2	Tens.	B1	G3
4	Units.	B2	G1

The first step is to open all the keys associated with these leads under the appropriate digits columns. These keys are shown in dashed lines in Figures 13a and 13b and 14. The next step is to build up the search circuit by connecting the selector switches 29, 34 corresponding to these BG combinations in series by means of plug-ended cords inserted in the jacks of panel 16. This has been done in Figure 14 whereby the search circuit may be traced in Figures 13a, 13b and 14 as follows: from the grounded side of the power source through jack 136, cord 147, G1 lower jack 134 in the units column, G1 switch elements 34 and 29, G1 upper jack 134 in the units column, cord 148 to B2 lower jack 134 in the units column, B2 switch elements 34 and 29, B2 upper jack 134 in the units column, cord 149 to B1 upper jack 134, in the tens column, B1 switch elements 29 and 34, B1 lower jack 134 in the tens column, cord 150 to G3 upper jack 134 in the tens column, G3 switch elements 29 and 34, G3 lower jack 134 in tens column, cord 151 to G1 lower jack 134 in the hundreds column, G1 switch elements 34 and 29, G1 upper jack 134 in the hundreds column, cord 152 to B1 lower jack 134 in the hundreds column, B1 switch elements 34 and 29, B1 upper jack 134 in hundreds column, cord 153 to B1 upper jack 134 in thousands column, B1 switch elements 29 and 34, B1 lower jack 134 in thousands column, cord 154 to G4 upper jack 134 in thousands column, G4 switch elements 29 and 34 to G4 lower jack 134 in thousands column, cord 155 to G2 lower jack 134 in ten thousands column, G2 switch elements 34 and 29 to G2 upper jack 134 in ten thousands column, G2 switch elements 34 and 29 to G2 upper jack 134 in ten thousands column, cord 156 to B2 lower jack 134 in ten thousands column, B2 switch elements 34 and 29 to B2 upper jack 134 in ten thousands column, cord 157 to B2 upper jack in hundred thousands column, B2 switch elements 29 and 34 to B2 lower jack 134 in hundred thousands column, cord 158 to G4 upper jack 134 in hundred thousands column, G4 switch elements 29 and 34 to G4 lower jack 134 in hundred thousands column, cord 159 to power jack 135, search lamp 137, and thence by way of power switch 139 to the live side of the power source.

Tape 18 is now fed through selector mechanism

23 by operation of crank 43 until search lamp 137 is lighted, this occurring when the punchings in the tape corresponding to the predetermined number 753024 move into the selector switch mechanism whereby the aforetraced circuit is completed through the punchings in the tape to energize lamp 137. Lever 84 of the rocker arm assembly is now moved downwardly to cause the multiplier, quantity, and installation and retirement data relating to the predetermined unit of property to be recorded on paper 95. The entire tape is scanned or searched in this manner to get all the information thereon relating to the presented unit 753024, a typing operation being performed each time search lamp 137 is lighted. The record thus obtained will constitute a summary sheet for this unit of property.

Whereas in the foregoing one example of selective typing has been given with a unit of property 20 as the basis of selection, it will be understood that other items such as, the installation or retirement dates may be made the basis of selection and similar steps are followed in building up the search circuits.

25 In some cases it may be desirable to have a bank or panel of numbered lamps, corresponding to the rows of sliding contacts 90 and 91 and terminating in the same combination of B and G leads, for visually indicating the circuits established by the punchings in tape 18. To this end, the lamp panel may either be connected in parallel with the sliding contact panel 89 by connecting the appropriate B and G leads of the lamp panel into the upper B and G jacks, or the lamp panel may be substituted for the sliding contact panel which in this case is cut out of the control circuits entirely, by opening all of the upper keys and then connecting the lamp B and G leads into the upper jacks.

30 35 40 From the foregoing it should now be apparent that a typing machine has been provided which is well adapted to fulfill the aforeslated objects of the invention and to expeditiously and effectively perform essential and time saving operations and steps in the setting up of history and summary sheets for use in a continuous property record system.

45 Whereas the invention has been disclosed in particularity with respect to a preferred embodiment thereof with selected operations of the embodiment being given for the purpose of illustration, it will be understood by those skilled in the art to which the invention most closely appertains, after obtaining an understanding of the invention, that the same is susceptible of additional embodiments and modes of operation and 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 moved successively opposite the typing roller as the typing bars are pivoted about said axis, an inking ribbon interposed between the paper on the typing roller and the arcuate surfaces of the typing bars, rocker means including a manually operative lever and adapted to be moved concentrically about said axis from an initial position to a typing position as the typing machine is operated, a plurality of operate magnets carried by said rocker means and individual to said plurality of typing bars, said operating magnets being adapted to engage the typing bars for movement therewith from the moment the magnets are energized during movement of said lever between said initial and typing positions thereof, a plurality of circuits under control of the punchings in the tape for energizing the magnets at predetermined spaced intervals during movement of the operating lever, said spaced intervals being in accordance with the punchings in the tape for a given section thereof corresponding to a line of typing on the machine whereby imprint characters on the typing bars corresponding to the punchings in the tape are moved opposite the typing roller into typing relation therewith as the operating lever is moved into the typing position thereof, and means adapted to be driven by said rocker means as the operating lever is moved into its typing position for moving the typing roller and the paper thereon into typing engagement with the imprint characters aligned therewith.

2. In a typing machine of the character disclosed for typing from a punched tape, the combination of a typing roller, a plurality of identical typing bars arranged for pivotal movement about an axis disposed transversely thereof, each of said bars having an arcuate surface adjacent said typing roller and a plurality of imprint characters disposed in spaced relation on the arcuate surface whereby the characters successively are moved diametrically opposite the typing rollers as the bar is pivoted about said axis, rocker means including a panel and a manually operable lever carried thereby arranged for concentric movement to a typing position, a plurality of operate magnets carried by said panel and individual to said plurality of typing bars, each of said operate magnets having an armature for engaging the typing bar individual thereto for movement therewith from the moment the winding of the operate magnet is energized during movement of the panel from said initial position to said typing position, a plurality of pairs of moving contacts respectively connected to the windings of the operate magnets and carried by said panel, a plurality of rows of stationary contacts individual to said plurality of pairs of moving contacts and adapted to be engaged thereby as the panel moves, each row of contacts comprising a plurality of pairs of contacts corresponding respectively to the plurality of imprint characters on the typing bars individual thereto and correspondingly spaced concentrically about the pivotal axis of the bars, and a plurality of circuits individual to said rows of contacts and said plurality of moving and companion switch elements for connecting predetermined pairs of contacts therein to a source of power selectively in accordance with the punchings in the tape whereby the typing bars are moved to bring imprint characters corresponding to the tape punchings into printing relation with respect to the roller when the operating lever is moved to the typing position thereof.

3. In a typing machine of the character dis-

closed for typing from a punched tape, the combination of a typing roller, a plurality of identical typing bars arranged for pivotal movement about an axis disposed transversely thereof, each of said bars having an arcuate surface adjacent said typing roller and a plurality of imprint characters disposed in spaced relation on the arcuate surface whereby the characters successively are moved diametrically opposite the typing rollers as the bar is pivoted about said axis, rocker means including a panel and a manually operable lever carried thereby arranged for concentric movement to a typing position, a plurality of operate magnets carried by said panel and individual to said plurality of typing bars, each of said operate magnets having an armature for engaging the typing bar individual thereto for movement therewith from the moment the winding of the operate magnet is energized during movement of the panel from said initial position to said typing position, each typing bar having a plurality of ratchet teeth arranged diametrically opposite said imprint characters and corresponding thereto, each of said armatures being pawl shaped to engage the ratchet teeth in the typing bar individual thereto, a plurality of pairs of moving contacts respectively connected to the windings of the operate magnets and carried by said panel, a selector switch mechanism having a plurality of movable switch elements in contact with the tape and adapted to contact companion switch elements individual thereto as punchings in the tape move under said moving switch elements, a plurality of rows of stationary contacts individual to said plurality of pairs of moving contacts and adapted to be engaged thereby as the panel moves, each row of contacts comprising a plurality of pairs of contacts corresponding respectively to the plurality of imprint characters on the typing bars individual thereto and correspondingly spaced concentrically about the pivotal axis of the bars, and a plurality of circuits individual to said rows of contacts and said plurality of moving and companion switch elements for connecting predetermined pairs of contacts therein to a source of power selectively in accordance with the punchings in the tape whereby the typing bars are moved to bring imprint characters corresponding to the tape punchings into printing relation with respect to the roller when the operating lever is moved to the typing position thereof.

4. In a typing machine of the character disclosed for typing from a punched tape, the combination of a typing roller, a plurality of identical typing bars arranged for pivotal movement about an axis disposed transversely thereof, each of said bars having an arcuate surface adjacent said typing roller and a plurality of imprint characters disposed in spaced relation on the arcuate surface whereby the characters successively are moved diametrically opposite the typing rollers as the bar is pivoted about said axis, rocker means including a panel and a manually operable lever carried thereby arranged for concentric movement to a typing position, a plurality of operate magnets carried by said panel and individual to said plurality of typing bars, each of said operate magnets having an armature for engaging the typing bar individual thereto for movement therewith from the moment the winding of the operate magnet is energized during movement of the panel from said initial position to said typing position, a plurality of pairs of moving contacts respectively connected to the windings of the operate magnets and carried by said panel, a selector switch mechanism having a plurality of movable switch elements in contact with the tape and adapted to contact companion switch elements individual thereto as punchings in the tape move under said moving switch elements, a plurality of rows of stationary contacts individual to said plurality of pairs of moving contacts and adapted to be engaged thereby as the panel moves, each row of contacts comprising a plurality of pairs of contacts corresponding respectively to the plurality of imprint characters on the typing bars individual thereto and correspondingly spaced concentrically about the pivotal axis of the bars, and a plurality of circuits individual to said rows of contacts and said plurality of moving and companion switch elements for connecting predetermined pairs of contacts therein to a source of power selectively in accordance with the punchings in the tape whereby the typing bars are moved to bring imprint characters corresponding to the tape punchings into printing relation with respect to the roller when the operating lever is moved to the typing position thereof.

75 respectively connected to the windings of the

operate magnets and carried by said panel, a plurality of rows of stationary contacts individual to said plurality of pairs of moving contacts and adapted to be engaged thereby as the panel moves, each row of contacts comprising a plurality of pairs of contacts corresponding respectively to the plurality of imprint characters on the typing bars individual thereto and correspondingly spaced concentrically about the pivotal axis of the bars, a selector switch mechanism adapted to receive the tape therethrough having a plurality of moving and companion switch elements in contact with the tape and adapted to make contact with each other as the moving elements move through the punchings in the tape, said selector mechanism having a row of pairs of moving and companion switch elements for each row of said stationary contacts, and a plurality of circuits for interconnecting corresponding pairs of contacts in each of said rows of stationary contacts to the selector switch elements in the rows of the elements individual thereto and to a source of electrical energy selectively in accordance with the tape punchings whereby the typing bars are moved to bring imprint characters corresponding to the tape punchings in the section of the tape within the selector mechanism into printing relation with respect to the typing roller as the operating lever is moved into the typing position thereof.

5. In a typing machine of the character disclosed for typing from a punched tape, the combination of a typing roller, a plurality of identical typing bars arranged for pivotal movement about an axis disposed transversely thereof, each of said bars having an arcuate surface adjacent said typing roller and a plurality of imprint characters disposed in spaced relation on the arcuate surface whereby the characters successively are moved diametrically opposite the typing rollers as the bar is pivoted about said axis, rocker means including a panel and a manually operable lever carried thereby arranged for concentric movement to a typing position, a plurality of operate magnets carried by said panel and individual to said plurality of typing bars, each of said operate magnets having an armature for engaging the typing bar individual thereto for movement therewith from the moment the winding of the operate magnet is energized during movement of the panel from said initial position to said typing position, a plurality of pairs of moving contacts respectively connected to the windings of the operate magnets and carried by said panel, a plurality of rows of stationary contacts individual to said plurality of pairs of moving contacts and adapted to be engaged thereby as the panel moves, each row of contacts comprising a plurality of pairs of contacts correspondingly respectively to the plurality of imprint characters on the typing bars individual thereto and correspondingly spaced concentrically about the pivotal axis of the bars, a selector switch mechanism adapted to receive the tape therethrough having a plurality of moving and companion switch elements in contact with the tape and adapted to make contact with each other as the moving elements move through the punchings in the tape, said selector mechanism having a row of pairs of moving and companion switch elements for each row of said stationary contacts, a plurality of circuits for interconnecting corresponding pairs of contacts in each of said rows of stationary contacts to the selector switch elements in the rows of the elements individual

thereto and to a source of electrical energy selectively in accordance with the tape punchings whereby the typing bars are moved to bring imprint characters corresponding to the tape punchings in the section of the tape within the selector mechanism into printing relation with respect to the typing roller as the operating lever is moved into the typing position thereof, a jack panel having a plurality of jacks connected in 5 said plurality of circuits, one of said jacks being connected to one of said movable selector switch elements and one each of the jacks being connected to one of said companion switch elements, and a key panel having a plurality of keys in said 10 plurality of circuits, one pair of said keys being connected respectively to the pair of jacks in each of said plurality of circuits.

6. In a typing machine of the character disclosed for typing from a punched tape, the combination of a typing roller, a plurality of identical typing bars arranged for pivotal movement about an axis disposed transversely thereof, each of said bars having an arcuate surface adjacent said typing roller and a plurality of imprint characters disposed in spaced relation on the arcuate surface whereby the characters successively are moved diametrically opposite the typing rollers as the bar is pivoted about said axis, rocker means including a panel and a manually operable lever carried thereby arranged for concentric movement to a typing position, a plurality of operate magnets carried by said panel and individual to said plurality of typing bars, each of said operate magnets having an armature for engaging the 25 typing bar individual thereto for movement therewith from the moment the winding of the operate magnet is energized during movement of the panel from said initial position to said typing position, a plurality of pairs of moving contacts 30 respectively connected to the windings of the operate magnets and carried by said panel, a plurality of rows of stationary contacts individual to said plurality of pairs of moving contacts and adapted to be engaged thereby as the panel moves, 35 each row of contacts comprising a plurality of pairs of contacts corresponding respectively to the plurality of imprint characters on the typing bars individual thereto and correspondingly spaced concentrically about the pivotal axis of the bars, a selector switch mechanism adapted to receive the tape therethrough having a plurality of moving and companion switch elements in contact with the tape and adapted to make contact with each other as the moving elements move 40 through the punchings in the tape, said selector mechanism having a row of pairs of moving and companion switch elements for each row of said stationary contacts, a plurality of circuits for interconnecting corresponding pairs of contacts in each of said rows of stationary contacts to the selector switch elements in the rows of the elements individual thereto and to a source of electrical energy selectively in accordance with the tape punchings whereby the typing bars are moved to bring imprint characters corresponding to the tape punchings in the section of the tape within the selector mechanism into printing relation with respect to the typing roller as the operating lever is moved into the typing position thereof, a jack panel having a plurality of jacks being connected to one of said movable selector switch elements and one each of the jacks being connected to one of said companion switch elements, a key panel having a plurality of keys in said 45 plurality of circuits, one pair of said keys

being connected respectively to the pair of jacks in each of said plurality of circuits, a location lamp connected across two of the circuits to a pair of selector switch movable elements which are located in the same row of switch elements and which do not complete a circuit to a pair of stationary contacts in the row of contacts individual thereto, and a search circuit connected to the source of electrical energy and including a search lamp, at least two pair of companion and movable selector switch elements, the jacks individual thereto, and a plurality of plug ended cords for engagement with the jacks.

7. The typing machine of claim 6 but further characterized in that the imprint characters on each of the typing bars number 0 to 9, each row of switch elements in the selector mechanism comprises seven pairs of movable and companion switch elements, three of seven leads of the first set of leads interconnect the movable switch elements of each row with one side of the pairs of stationary contacts in the row of contacts individual thereto, the other four of the seven leads interconnect the other four movable switch elements in each row with the other side of the pairs of stationary contacts individual thereto, three of a second set of seven leads interconnect the companion switch elements individual to said three movable switch elements with one side of the source of power, the other four of said second set of seven leads interconnect the companion switch elements individual to said four movable switch elements to the other side of the source of power, one of the three leads of said first set of seven leads being connected to stationary contacts corresponding to imprint characters 0 to 3, the second of the three leads being connected to stationary contacts corresponding to imprint characters 4 to 7, the third of the three leads being connected to stationary contacts corresponding to imprint characters 8 and 9, one of the four leads of the first set of leads interconnects stationary contacts corresponding to imprint characters 0, 4 and 8, the second of the four leads interconnects stationary contacts corresponding to imprint characters 1, 5 and 9, the third of the four leads interconnects stationary contacts corresponding to imprint characters 2 and 6, and the fourth of the four leads interconnects stationary contacts corresponding to imprint characters 3 and 7.

8. In a typing machine of the character disclosed for typing from a punched tape, the combination of a casing, a shaft supported for rotation in the casing, a plurality of typing bars pivotally supported on said shaft in predetermined spaced axial relation thereon and having diametrically opposed arcuate surfaces having arranged in spaced relation thereon a plurality of imprint characters and ratchet teeth respectively, a typing roller adjacent said arcuate surface having the imprint characters thereon, support means for the roller pivotally mounted on the casing and adapted to move the roller into contact with the imprint characters as the support means is pivoted about the pivot axis thereof, a rocker assembly pivotally supported on the shaft and including a panel having a manually operable handle thereon, a plurality of operate magnets carried by the panel and individual to said plurality of typing bars, said magnets having armatures adapted to engage the ratchet

teeth on the typing bars individual thereto from the moment the magnets are energized thereby to move the typing bars with the rocker assembly to a typing position thereof, a stationary panel concentrically arranged with respect to said shaft, a plurality of rows of stationary contacts on said stationary panel individual to said plurality of typing bars and operate magnets, each of said rows of stationary contacts comprising a plurality of pairs of predetermined spaced contacts, corresponding to the number and spacing of said imprint characters and ratchet teeth on the typing bar individual thereto, a plurality of pairs of contacts carried by the moving panel and individual to the rows of contacts on the stationary panel, each pair of moving contacts being adapted to engage the stationary contacts in the row of contacts individual thereto successively as the rocker arm assembly is moved from an initial position to said typing position thereof, a selector mechanism for receiving the tape and having a plurality of rows of switches individual to the plurality of rows of contacts on the stationary panel, each of said selector switches including an element adapted to be moved into a punching in the tape to close the switch, means for advancing the tape through the selector mechanism as said shaft is rotated, means for pivoting the roller support to move the roller into contact with the imprint characters as the rocker assembly is moved into its typing position, and a plurality of circuits individual to said rows of selector switches and said rows of stationary contacts individual thereto for energizing the operate magnets selectively at spaced intervals during the forward movement of the rocker assembly in accordance with the punchings in the tape whereby imprint characters corresponding thereto are moved into typing relation to the roller as the rocker assembly is moved into the typing positions thereof.

9. The typing machine of claim 8 but further characterized in that the machine comprises jack and key panels having respectively a plurality of jacks and a plurality of keys thereon connected in said plurality of circuits, a location lamp mounted on the jack panel and connected across a predetermined pair of said circuits, and means including a search lamp mounted on the jack panel for setting up any one of a plurality of search circuits through predetermined jacks which have been cut off from the typing control circuits by actuation of the keys individual thereto.

10. The typing machine of claim 8 but further characterized by the provision of means operable under control of the rocker assembly for advancing the shaft and the typing roller to new settings during the return movement of the rocker assembly.

SAMUEL M. TAYLOR.
